UNITED STATES PATENT OFFICE.

RUSSELL P. SULLIVAN, OF PITTSBURGH, PENNSYLVANIA, ASSIGNOR TO THE GIANT TIRE & RUBBER COMPANY, OF AKRON, OHIO, A CORPORATION OF OHIO.

DESIGN FOR AN ELASTIC VEHICLE-TIRE.

51,616.

Specification for Design.

Patented Dec. 18, 1917.

Application filed October 14, 1916. Serial No. 125,748. Term of patent 3½ years.

To all whom it may concern:

Be it known that I, RUSSELL P. SULLIVAN, a citizen of the United States, residing at Pittsburgh, in the county of Allegheny and State of Pennsylvania, have invented a new, original, and ornamental Design for Elastic Vehicle-Tires, of which the following is a specification, reference being had to the accompanying drawings, forming a part thereof.

In the drawings, Figure 1 is a front elevation of a portion of an elastic vehicle tire embodying this invention, and

Fig. 2 is a transverse sectional view taken approximately on line 2 of Fig. 1.

I claim,

The ornamental design for an elastic vehicle tire as shown.

RUSSELL P. SULLIVAN.
